UNITED STATES PATENT OFFICE.

ARTHUR BARLOW, OF NEW YORK, N. Y., ASSIGNOR OF ONE-HALF TO WALTER McDougall, OF BROOKLYN, NEW YORK.

HOLDER FOR NURSING-BOTTLES.

1,315,621.

Specification of Letters Patent.

Patented Sept. 9, 1919.

Application filed March 11, 1916. Serial No. 83,474.

To all whom it may concern:

Be it known that I, ARTHUR BARLOW, a citizen of the United States, and a resident of New York, borough of Brooklyn, in the 5 county of Kings and State of New York, have made and invented certain new and useful Improvements in Holders for Nursing-Bottles, of which the following is a specification.

10 This invention relates to a holder for nursing bottles, the object being to provide an article of this character, which is of neat and simple design and so constructed that it may be conveniently secured to a baby carriage, crib, or high chair or other articles 15 of furniture or support. The device is further so constructed and arranged that the bottle, which is supported thereby, may be quickly and easily brought within reach of 20 the infant or turned so as to be out of the way, all of which features being incorporated in a design which may be economically manufactured.

A further object is to provide a bottle 25 holder with support attachments therefor, each attachment being of such a nature that it is particularly adapted to engage, and be permanently secured to a high chair, a crib, or other articles of furniture, and the supporting portion of the device may be instantly secured to either of these attachments and also may quickly and easily be detached therefrom, thus allowing the device 30 to be transferred to different articles of furniture and thus always be within convenient 35 reach of the infant.

Other objects and advantages will appear as the description proceeds, wherein it is to be understood that changes in the 40 precise embodiment of my invention can be made within the scope of what is claimed, without departing from the spirit thereof.

The preferred embodiment of my invention is disclosed in the accompanying drawings, wherein:—

Figure 1 is a view in perspective of the supporting device, and diagrammatically illustrating a bottle secured thereto;

Fig. 2 is a detailed view in top plan of

the bottle supporting end of the device, illustrating, by dotted lines, the manner in which the bottle clamp may revolve; 50

Fig. 3 is a view in section of the bottle supporting end of the device taken on a plane at right angles to the plane of Fig. 2, 55 and illustrating the hinged joint upon which the clamp is mounted, and by means of which it may revolve;

Fig. 4 is a detailed view in section of the supported end of the device, and illustrating a bracket which is adapted to engage a post of a high chair or a similar article of furniture; 60

Fig. 5 is a top plan view of this type of supporting bracket; 65

Fig. 6 is a detailed view in perspective of a somewhat different form of supporting bracket, this type providing for a large range of adjustment and being particularly adapted for use upon cribs or similar 70 articles of furniture;

Fig. 7 is a view in front elevation of this latter type of supporting bracket.

Referring specifically to the several views, the main arm 10 is provided at one extremity with the right angle and turned supporting end 11, this extremity being the one which is adapted to engage the several types of brackets, and be supported thereby. The opposite extremity of the main arm has secured thereto the circular and spaced plates 12, the same in conjunction with a hub 13 and inner plates 14, constituting a hinged joint, and to which the bottle clamp is secured. The plates 12 are each provided 80 with the semi-cylindrical extensions 12' which fit within and rigidly engage the free end of the main arm 10. 85

The bottle clamp 15 is preferably formed of a single length of spring metal, bent in 90 the form of a circle and to the middle of which is fixedly secured a sleeve 16. The inner plates 14 of the hinged joint are provided with the radially extending semi-cylindrical shafts, fitting within and interlocking with the sleeve 16, and thus rotatably support the bottle clamp. The bottle clamp 95 is accordingly mounted for rotation about

a diametric axis, *i. e.* an axis at right angles to the longitudinal axes of the bottle, and is also capable of angular movement or adjustment about an axis at right angles thereto, that is about the axis of the hinge connection or joint provided by the plates 12 and 14 and the hub 13. This practically universal support of the bottle provides for a large range of adjustment thereof, and 10 renders the bottle conveniently accessible at all times.

In order that the bottle may be brought within reach of the infant, as well as adjusted with regards to its local position, the 15 main arm is provided with the turned supporting end 11, the extremity of which is hollow, and thus adapted to rotatably engage a post 17, which is carried by the supporting bracket 18. The supporting bracket 20 is stamped from a blank sheet of metal and comprises a yoke 19, which is adapted to embrace an upstanding portion of a chair, crib or allied article of furniture, and by means of a thumb or clamping screw 20 rigidly 25 and fixedly engage the same. Projecting from the upper and lower extremities of this yoke are the supporting plates 21 and 22, the upper plate 21 being provided with an opening 23 therein, and through and beyond 30 which extends the split post 17, this post being fixedly secured to and supported by the lower plate 22 and is somewhat smaller in diameter than the opening 23 in the upper plate. The turned supporting end 11 of the 35 main arm is adapted to fit down over the split post 17 and pass between the said post and the side walls of the opening 23 and, bearing down upon the lower plate 22, be supported thereby. The post 17 being split, 40 prevents the accidental removal of the main arm from the supporting bracket and the opening within the upper plate provides a bearing for the turned end of the main arm, and thus prevents undue pressure and lever- 45 age being brought to bear upon the post 17. The above-outlined, construction of the bracket allows it to be economically manufactured and the upper extremity of the post, being provided with a rounded end, allows 50 the main arm to be conveniently and easily positioned thereon, and when so located, forms an efficient bearing therefor.

In some instances it is preferable to provide a supporting post for the main arm 55 which may be adjusted with regard to its height and inclination, and, with this in view, the somewhat different form of bracket is provided, as illustrated in Figs. 6 and 7, this type of bracket being particularly efficient for use with baby carriages and other articles of furniture. In this type of bracket, a circular disk 24 is provided, and is formed with a raised rim 25, in which are formed

the diametrically arranged notches 26. The disk is provided with a central opening 27, 65 through which passes a bolt 28, the outer extremity of which is threaded and provided with the thumb or wing nut 29, and the remote and headed extremity carries a U-shaped clamp 30. This clamp, which includes the spaced and apertured arms 31, is adapted to be drawn against the outer surface of the notched rim by the wing nut and bolt, and, in so doing, the rod 32, which extends through the openings in the arms of 75 the clamp, is brought into adjusted and fixed contact with the notched rim, and is so held. The upper extremity 33 of the rod is somewhat reduced in diameter, and is rendered 80 resilient by the opening 34, which extends lengthwise thereof. This reduced upper extremity forms a post which is adapted to frictionally receive the turned and supporting end of the main arm thereon, and provide a support therefor, the shoulder, formed 85 by the reduction in diameter of the upper extremity of the rod, constituting a ledge 35 upon which the lower extremity of the supporting end of the main arm is adapted to rest. With this type of bracket not only is 90 the main arm adapted to swing about its turned end, but the axes, about which it swings, may be adjusted at various angles and the main arm also raised and lowered.

With the various types of brackets, as 95 thus described, a single main supporting arm may be utilized for supporting a bottle upon a high chair, crib or baby carriage, and forms an efficient support for a bottle, which may be easily and conveniently maintained within reach of an infant.

The supporting of the post incorporates a sufficient amount of resiliency therein, so that it frictionally engages the side walls of the turned supporting end of the main arm, 105 and prevents the accidental detachment thereof, and also causes the bottle to remain stationary in its adjusted positions.

What I claim is:—

1. A bottle supporting device comprising 110 a main arm with a hollow supporting end extending at an angle thereto, a bottle clamp carried by said arm and mounted for movement in different planes; a bracket provided with means for clamping it to a supporting structure and having plates spaced apart from each other, and a post carried by one of said plates and extending through an opening provided in the other, said post being adapted to enter the hollow supporting 115 end of said main arm.

2. A bottle supporting device including a main arm, spaced plates provided with confronting and radially extending semi-cylindrical members fixedly engaging said main 120 arm, a pair of plates pivotally secured to

and embraced between the aforementioned plates and provided with radially extending semi-cylindrical members collectively forming a shaft, a bottle clamp, a sleeve carried thereby and rotatably engaging said shaft, the axis of which latter extends at an angle to the axis of the pivotal mounting of the inner plates.

Signed at New York, borough of Brooklyn, in the county of Kings and State of New York, this 7th day of March, A. D. 1916.

ARTHUR BARLOW.
